UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

WIRELESS SIGNALING SYSTEM.

Original application filed April 19, 1916, Serial No. 92,156. Patent No. 1,465,961, dated August 28, 1923.
Divided and this application filed July 18, 1918, Serial No. 244,840. Renewed July 12, 1920. Serial No. 395,762.

To all whom it may concern:

Be it known that I, ERNST F. W. ALEXANDERSON, a citizen of the United States, residing at Schenectady, county of Schenectady, State of New York, have invented certain new and useful Improvements in Wireless Signaling Systems (division of my application filed April 19, 1916, Serial No. 92,156, now Patent No. 1,465,961, dated 10 Aug. 28, 1923), of which the following is a specification.

My present invention relates to wireless signaling systems, and more particularly to a system in which means is provided for 15 overcoming the effect of static disturbances in the receiving instruments.

Electrostatic disturbances occur continuously in the atmosphere, sending out electromagnetic waves of varying frequency, 20 which will in the description which follows be referred to as strays. These waves are absorbed by the receiving antenna and among the variety of waves absorbed there are always some which are in resonance, 25 that is, which have the same length as a signal which is to be received and consequently act upon the receiving devices in the same way as the signal. Having analyzed this condition both mathematically 30 and experimentally, I have come to the conclusion that a fundamental rule must be the basis of any device used for decreasing the effect of static disturbances. Any discrimination 35 between a wave of the same frequency originating from static and from the signal must be based on some difference in character between these two waves. If the strays were like the signals both in frequency and amplitude variation, and in 40 addition to that stronger than the signals, there would be no way conceivable for discriminating between one and the other. The longer the period is during which the strays 45 and the signaling waves can be compared, the greater is the chance for finding a distinguishing difference in the sequence of amplitude variations if in nothing else. In order that the device be effective for discrimination against strays, it should therefore be designed so that the wave trains 50 can be distinguished by comparing their character for sufficiently long periods. The receiving devices which are at present used

commercially are constructed so as to take advantage of this law to a certain extent 55 by using a highly resonant receiving circuit on which the signal can be allowed to act for a considerable number of successive alternations. The reason why these devices do not entirely discriminate against strays 60 is the fact that the receiving antenna is set in oscillation by static shocks and stray waves of short duration and thus the time during which the disturbance can act upon the receiving device is prolonged to about 65 the same degree as the signal.

One of the objects of my invention is to provide a means for prolonging the time during which the signal can act with accumulative effect on the receiving device 70 considerably beyond the time during which disturbances can act.

In attaining this object I make use of a tuned circuit of lower than radio frequency, but above audibility, for effecting the prolongation of the time during which the signal and disturbance may be compared. The desired lower frequency is provided by means of interference beats between two radio frequencies. Both of these frequencies may be produced at the sending station, but in the present application one of them is produced at the receiving station. An arrangement of this kind is more effective than one employing a single radio frequency because it is more selective and proof 85 against interference, both frequencies being necessary to produce an impression in the receiver. Also when means is provided at the sending station for establishing the beat 90 frequency a less delicate adjustment of frequency is necessary than when the beat frequency is the result of the difference between two high frequencies. A further object of my invention is to provide means 95 for efficiently producing signals of the desired character. Another object of my invention is to provide suitable receiving apparatus for rendering audible at the receiving station the signals sent from the transmitting station and for enabling the receiving operator to readily distinguish between effects produced by the static shocks and those produced by the desired signal. Still another object of my invention is to 100 provide a means for limiting the amount 105

of energy of the static shocks which can be transmitted to the receiving apparatus without at the same time limiting the energy of the signal which will act upon the receiving apparatus.

The features of my invention which I believe to be patentable are pointed out with particularity in the appended claims. The invention itself however, together with further objects and advantages thereof, will best be understood by reference to the following description taken in connection with the accompanying drawing in which Figs. 1 and 2 illustrate different modifications of the circuit connections which may be employed in receiving signals in accordance with my invention.

In the circuit arrangement shown in Fig. 1, continuous wave signals are received upon the antenna 1 which may be aperiodic or strongly damped, so that it will not be set into oscillation by static shocks. A high frequency source of current 2 is also coupled to the antenna 1 by means of a coupling transformer 3. The local source of current should be of a frequency differing from that of the received signals by an amount above audibility. The current having amplitude pulsations which results from the interaction between the current from the local source and the signaling current is impressed upon a circuit which includes the grid 4 of an amplifier 5 of the electron discharge type comprising a heated cathode 6 and cooperating anode 7 with a battery 8 in the external circuit between cathode and anode. A few of the cells 9 of this battery may also be connected between cathode and grid in order to adjust the grid potential to a value at which the device is most efficient in amplifying the received signals. The current flowing in the circuit of this amplifier which comprises electrodes 6 and 7, and battery 8, which for convenience in description I designate the plate circuit, will be a pulsating current. The alternating current component of this current will flow in the secondary of transformer 10 and the circuit 11 which comprises the secondary of this transformer, inductance 12, and variable condenser 13 is tuned to the frequency of the amplitude pulsations of the current impressed upon the amplifier 5. The impulses act accumulatively until the current in circuit 11 has attained its maximum amplitude. If this circuit is a highly tuned circuit the time during which the current amplitude will be built up may be as much as that covered by 100 cycles of the amplitude pulsations; that is, if the frequency of these pulsations is 5000 cycles it may require 1/50 of a second for the oscillating circuit 11 to reach this maximum. If the radio frequency is 50,000 cycles the time for the oscillating circuit 11 to reach its maximum

may correspond to 1000 cycles of the radio frequency and thus it is apparent that the energy stored in the oscillating circuit may represent the accumulated energy of 1000 cycles of the radio frequency. The antenna 70 as well as the secondary oscillating circuit will also be affected by static shocks and to a certain degree accumulatively. However, it can be proven by the law of probability that the accumulative effect of successive 75 static shocks in any oscillating circuit increases by the square root of the time in which these irregular shocks are taking place, whereas the oscillations due to the signal, if this is a continuous wave, increases 80 arithmetically until the circuit has approached its maximum amplitude. While it can therefore not be expected that the secondary oscillating circuit will be free 85 from static disturbances the relative intensity of the signal and the static is greater the longer the time during which the energy of the signal can accumulate. In order to make the signal audible a local source of alternating current 14 of slightly 90 different frequency from that of the current in circuit 11 is introduced in the grid circuit of amplifier 15, so as to create beats in the receiver 16 which is inserted in the plate circuit of this amplifier and detect the current of secondary frequency by the well known heterodyne method. In previous attempts which have been made to suppress static by tuning for an audible group frequency in a spark system or its equivalent, 95 the operator has been required to distinguish between the signal and static by the pitch of the note which is heard in the receiving telephone. In this case although 100 tuning is applied to the circuit of the audible group frequency and the intensity of the currents produced by static relative to the intensity of the signal has been decreased in somewhat the same manner as that described, there has been practically 105 no gain by reason of this action because of the fact that the currents produced by static are changed to a pitch for which the ear is particularly sensitive, and in fact, are 110 changed to a pitch similar to the signal. In 115 my system, however, in which the secondary tuning is at an inaudible frequency the receiving device discriminates between currents of the static and the signal purely by magnitude and the tone pitch at which the 120 signal is received is regulated independently by the heterodyne receiver without reference to the frequency of the discriminating oscillatory circuit.

In the arrangement shown in Fig. 2, I 125 have illustrated an additional safeguard against the transmission of static shocks to the receiving circuit in which an iron core transformer is substituted for the transformer 10 of Fig. 1. This transformer is 130

so designed that the normal strength of a signal will work the iron at its maximum permeability whereas any sudden and excessive shocks by static will saturate the iron 5 so that full force of the shock will not be transmitted to the secondary. This transformer is, in other words, a voltage limiting transformer which is capable of transmitting without saturation a voltage only 10 slightly in excess of that produced by the signals. As indicated in the drawing the transformer in the present case comprises two cores 17 and 18, each having a primary winding 19 and a secondary winding 20. 15 In order to regulate the saturation of this transformer a third winding 21 which is common to the two cores, is supplied with a direct current from battery 22, and the value of the current thus supplied may be 20 adjusted in order to secure the desired degree of saturation.

While I have shown and described only two different receiving systems whereby my invention may be carried into effect, it is apparent 25 that many modifications may be made in the circuit arrangements as well as in the particular form of apparatus used without departing from the scope of my invention as set forth in the appended claims.

30 What I claim as new and desire to secure by Letters Patent of the United States, is,—

1. The method of receiving continuous wave signals which consists in combining the received current with the current from a local source differing therefrom in frequency so that beats are produced having a frequency above audibility, amplifying and rectifying the current thus produced, passing the rectified current through a circuit 40 which is resonant to the frequency of the beats, and then rectifying the alternating current flowing in this resonant circuit.

2. The method of receiving wireless signals which consists in combining the signaling current with a local source of high frequency current so as to produce a current of radio frequency with amplitude pulsations of much lower frequency but above audibility, producing from this current having amplitude pulsations an alternating current having a frequency corresponding to the frequency of the amplitude pulsations, accumulating the energy of this alternating current in a resonant circuit and utilizing 50 the accumulated energy for the operation of suitable detecting apparatus.

3. The method of receiving wireless signals which consists in combining the signaling current with a current having a frequency differing therefrom by an amount above audibility, producing from these currents an alternating current with a frequency corresponding to the difference between the frequencies of the two currents, 60 accumulating the energy of the last named

alternating current during a plurality of successive cycles and selectively detecting the energy thus accumulated.

4. The method of receiving wireless signals which consists in producing at the receiving station a radio frequency current having definite amplitude pulsations of a frequency above audibility by causing the signaling current to interact with a local source of high frequency current, producing 70 an alternating current of a frequency corresponding to the said amplitude pulsations, and selectively receiving and detecting the alternating current thus produced.

5. The combination in a wireless signaling system, of an antenna for receiving continuous wave signaling currents, a local source of current of radio frequency differing in frequency from the signaling current by an amount above audibility, means 80 for combining the signaling current with current from the local source to produce an alternating current having a frequency above audibility, a resonant circuit for accumulating the energy of the current thus 85 produced, and means for detecting the energy thus accumulated.

6. The combination in a wireless signaling system, of an antenna for receiving continuous wave signaling current, a local source of 90 current of radio frequency, means for combining the signaling current with current from the local source to produce a current of radio frequency having amplitude pulsations of much lower frequency, but above audibility, means for producing from this current an alternating current having a frequency corresponding to the frequency of the amplitude pulsations, a resonant circuit for accumulating the energy of this alternating 100 current, and detecting apparatus adapted to be operated by the energy thus accumulated.

7. The combination in a wireless signaling system, of means at a receiving station for combining a continuous wave signaling 110 current with a current from a local source having a frequency differing therefrom by an amount above audibility, means for producing from the combined currents an alternating current having a frequency corresponding to the difference between the frequencies of the two currents, a resonant circuit for accumulating the energy of this alternating current during a plurality of successive cycles, and means for detecting the 120 energy thus accumulated.

8. The combination in a wireless signaling system, of means at a receiving station for combining a signaling current with current from a local source of radio frequency 125 to produce a radio frequency current having definite amplitude pulsations of a frequency above audibility, means for producing from said current having amplitude pulsations, an alternating current having a fre- 130

- frequency corresponding to the amplitude pulsations, and means for selectively receiving and detecting the alternating current thus produced.
- 5 9. The method of overcoming the effects of static disturbances in a wireless signaling system, which consists in receiving the signals by means of a substantially aperiodic antenna, producing at the receiving station 10 by means of the received signals and a local source a current of radio frequency having amplitude pulsations of much lower frequency, amplifying the current thus produced and producing thereby an alternating 15 current having a frequency corresponding to the amplitude pulsations, and passing this current through a circuit containing a device for limiting the energy passing therethrough to a predetermined value, and then 20 through a circuit which is resonant to the frequency of the alternating current.
10. The combination in a wireless receiving system, of a substantially aperiodic antenna, means for amplifying the signaling 25 current received thereby, and an iron core transforming device in the circuit of the amplified current so adjusted that voltages appreciably exceeding those produced by the signal will not be transmitted thereby.
- 30 11. The combination in a wireless receiving system, of an antenna, means for amplifying the signaling current received thereby, and an iron core transforming device in the circuit of the amplified current so adjusted 35 that voltages appreciably exceeding those produced by the signals will not be transmitted thereby.
12. The method of receiving continuous 40 wave signals which consists in combining the received current with the current from a local source differing therefrom in frequency so that beats are produced having a frequency above audibility, rectifying the current thus produced, producing from this 45 rectified current an alternating current having a frequency equal to the beat frequency passing the last mentioned current through a circuit which is resonant to its frequency and amplifying and detecting the alternating 50 current of beat frequency.
13. The method of receiving wireless signals which consists in combining the signaling current with a local source of high frequency current so as to produce a current of 55 radio frequency with amplitude pulsations of much lower frequency but above audibility, producing from this current having amplitude pulsations an alternating current having a frequency corresponding to the frequency of the amplitude pulsations passing the last mentioned current through a circuit which is resonant to its frequency, and amplifying and detecting the alternating current flowing in said circuit.
- 60 14. The method of receiving wireless signals which consists in producing at the receiving station a radio frequency current having definite amplitude pulsations of a frequency above audibility by causing the signaling current to interact with a local 70 source of high frequency current, producing an alternating current of a frequency corresponding to the said amplitude pulsations applying the resultant current to the input circuit of an electron discharge device, and thereby amplifying and detecting the alternating current thus produced.
15. The combination in a wireless signaling system, of an antenna for receiving continuous wave signaling currents, a local 80 source of current of radio frequency differing in frequency from the signaling current by an amount above audibility, means for combining the signaling current with current from the local source to produce an alternating current having a frequency above audibility, a circuit through which said alternating current is passed and which is resonant to the frequency thereof and means for amplifying and detecting the alternating current flowing in said circuit.
16. The combination in a signaling system of means at a receiving station for combining a continuous wave signaling current with a current from a local source having a 85 frequency differing therefrom by an amount above audibility, means for producing from the combined currents an alternating current having a frequency corresponding to the difference between the frequencies of 90 the two currents, and an electron discharge device for amplifying and detecting the alternating current produced thereby.
17. The combination in a wireless signaling system, of means at a receiving station 105 for combining a signaling current with current from a local source of radio frequency to produce a radio frequency current having definite amplitude pulsations of a frequency above audibility, means for producing from 110 said current having amplitude pulsations, an alternating current having a frequency corresponding to the amplitude pulsations, and an electron discharge device for amplifying and detecting the alternating current 115 thus produced.
18. The method of amplifying and receiving high frequency electrical oscillatory energy which comprises combining the incoming energy with locally generated high 120 frequency continuous oscillations of a frequency differing from said incoming energy by a third high frequency, converting the combined energy by suitable means to produce said third high frequency oscillations, applying the resultant current to the input circuit of an electron discharge amplifier and thereby amplifying, detecting and indicating the said third high frequency oscillations.

19. The method of amplifying and receiving high frequency electrical oscillatory energy which comprises, combining the incoming energy with locally generated high frequency continuous electrical oscillations of a frequency differing from said incoming energy by a third high frequency, rectifying the combined energy to produce said third high frequency oscillations, passing said third high frequency oscillations through a circuit which is resonant to this frequency and amplifying, detecting and indicating the said third high frequency oscillations.
- 10 20. The method of amplifying and receiving undamped wave high frequency electrical oscillatory energy which comprises combining the incoming energy with locally generated high frequency continuous electrical oscillations of a frequency differing from said incoming energy by a third readily-amplifiable high frequency, amplifying
- the said third high frequency oscillations, combining said third high frequency electrical oscillations with locally generated 25 high frequency oscillations at a frequency near to said third high frequency, converting the said last combined energy to produce low frequency oscillations and indicating the resulting low frequency oscillations. 30
21. The method of indirectly amplifying high frequency electrical oscillatory energy which comprises combining said energy with high frequency continuous electrical oscillations of a frequency differing from said energy by a third readily-amplifiable high frequency, converting the combined energy by suitable means to produce said readily-amplifiable high frequency oscillations and amplifying said resulting readily-amplifiable high frequency oscillations. 35

In witness whereof, I have hereunto set my hand this 13th day of July, 1918.

ERNST F. W. ALEXANDERSON.

DISCLAIMER

1,508,151.—*Ernst F. W. Alexanderson, Schenectady, N. Y. WIRELESS SIGNALING SYSTEM.* Patent dated September 9, 1924. Disclaimer filed November 16, 1931, by the assignee, *Radio Corporation of America*.

Hereby enters this disclaimer to claim 21 in the said specification which is in the following words, to wit:

“The method of indirectly amplifying high frequency electrical oscillatory energy which comprises combining said energy with high frequency continuous electrical oscillations of a frequency differing from said energy by a third readily-amplifiable high frequency, converting the combined energy by suitable means to produce said readily-amplifiable high frequency oscillations and amplifying said resulting readily-amplifiable high frequency oscillations.”
